UNITED STATES PATENT OFFICE.

GEORGE GILL, OF BRIDGEPORT, CONNECTICUT, ASSIGNOR TO THE ROGERS & BRITTIN SILVER COMPANY, OF SAME PLACE.

DESIGN FOR A SPOON OR FORK HANDLE.

SPECIFICATION forming part of Design No. 13,178, dated August 15, 1882.

Application filed July 6, 1882. Term of patent 7 years.

To all whom it may concern:

Be it known that I, GEORGE GILL, a citizen of the United States, and a resident of Bridgeport, in the county of Fairfield and State of Connecticut, have invented a Design for Ornamenting the Handles of Spoons, Forks, &c., of which the following is a specification.

My invention is a design for the handles of spoons, forks, &c.; and it consists in ornamenting the same by the figures and forms as shown in the accompanying drawing, in which—

A represents the handle, and B. the bowl, blade, or prongs. Across the handle extend 15 fillets *a*, below which is a pendent rosette, *b*. Between the fillets and the end of the handle is a diagonal band, *c*, having ornamental borders or edgings *d d*, and ornamented by a se-

ries of rosettes, *e*, as shown. Between the fillets and the band is the stem of a vine having 20 leaves *f*, a flower, *g*, and terminal buds, *h*, and directly above the fillets is a cancellated ornament, *i*. From the upper side of the band *c* extend branches having flowers *j*, as shown.

I claim—

The design for the handle of a spoon or other article, ornamented by the figures and forms *a* to *j*, substantially as shown in and by the accompanying drawing.

In testimony whereof I have signed my name 30 to this specification in the presence of two subscribing witnesses.

GEORGE GILL.
